UNITED STATES PATENT OFFICE.

WALTER O. SNELLING, OF PITTSBURGH, PENNSYLVANIA.

ELECTRIC SAFETY-FUSE.

1,288,724.

Specification of Letters Patent. Patented Dec. 24, 1918.

Application filed March 22, 1915, Serial No. 16,003. Renewed June 8, 1918. Serial No. 239,041.

To all whom it may concern:

Be it known that I, WALTER O. SNELLING, a citizen of the United States, and a resident of Pittsburgh, in the county of Allegheny and State of Pennsylvania, have invented a new and useful Improvement in Electric Safety-Fuses, of which the following is a specification.

My invention relates to electric circuit 10 interrupters of the fuse type, which embody a fusible element adapted to melt and to thereby interrupt the circuit when the current therein reaches a predetermined value, and it has special reference to safety fuses, 15 in which the fusible element is associated with means for preventing destructive arcing at the instant when the fusible element melts or "blows".

The object of my invention is to provide 20 a circuit interrupter of the safety fuse type which shall embody means for surrounding the fuse, at the instant of fusion, with an inert atmosphere in which combustion cannot occur, whereby the ignition of inflammable objects in the vicinity of the fuse is 25 entirely prevented.

More particularly, the object of my invention is to provide a fusible element for safety fuses that shall have associated with 30 it a solid or semi-solid body which is vaporizable at the heat of fusion of the fusible element and which, when vaporized, produces an atmosphere that will neither burn nor support combustion. This mass of vapor 35 performs the double function of absorbing and rendering latent a large portion of the heat produced by the "blowing" fuse, and of forming an atmosphere in which combustion cannot occur. As sources of 40 such fire-preventing vapors, certain solid and semi-solid halogenated carbon compounds are well suited.

Various embodiments of my invention are 45 illustrated in the accompanying drawing, in which Figure 1 is a side view, partly in elevation and partly in section, of a cartridge fuse constructed in accordance with my invention; Fig. 2 is a longitudinal sectional view of a modified form of cartridge 50 fuse; Fig. 3 is a side view, partly in elevation and partly in section, showing a fuse wire provided with a coating of vaporizable fire-preventing material; Fig. 4 is a plan view of a fuse strip or tape carrying spaced 55 bodies of fire-preventing material; Fig. 5

is a side view, partly in elevation and partly in section, showing a modified form of cartridge fuse; Fig. 6 is a longitudinal sectional view of another form of fuse, and Fig. 7 is a side elevational view, partly in 60 section, showing a modified method of applying my invention to a fuse wire.

The "blowing" of electric fuses is an ever-present source of fire danger, especially in high voltage circuits and where the fuses 65 are placed near inflammable material. The arcing of fuses may also cause inconvenience and damage when, as is frequently the case, a large number of fuses are mounted upon a single fuse board, where one fuse, when 70 it "blows", will sometimes strike an arc that is violent enough to set off a whole series of other fuses. Such a wholesale "blowing" of fuses will often disable a 75 whole distribution system.

For the purpose of avoiding the foregoing inconveniences and dangers, many safety fuses have been designed in which the fusible element is surrounded by a mass of finely divided refractory material, such 80 as asbestos, magnesia, silica, talc, limestone and the like. In other safety fuses, the fusible element is immersed in a body of liquid such as carbon tetrachlorid or a hydrocarbon oil of high flashing point, which is intended to quench the arc, and still other fuses are filled with metallic salts, such as 85 the alkali metal carbonates, which are supposed to diminish arcing. All of these arc-restraining substances are effective to a limited degree only, since the solid materials heretofore used will not prevent arcs from forming, and will not afford protection if the fuse container is ruptured by the arc, as frequently happens. Liquid arc-restraining 90 mediums are somewhat more effective, but they easily escape from their containers, and therefore require specially constructed and often complicated receptacles. Carbon tetrachlorid, on account of its solvent action upon many organic substances, requires 95 particularly careful selection and construction of containers.

According to my present invention, I effectively prevent destructive arcing of fuses 100 by the use of solid or semi-solid fire-preventing substances, which may be readily and inexpensively applied to existing forms of fuses, both open and inclosed, and which require no special receptacles. A large num- 110

ber of substances are suitable for use as the fire preventing agents, but at present, I prefer to make use of certain halogenated carbon compounds, particularly chlorin 5 polysubstitution products of ethane, propane, naphthalene and other hydrocarbons, both aliphatic and aromatic. Of these polyhalogenated bodies, I find the following to be efficient agents for my present purpose: ethane pentabromid C_2HBr_5 ; ethane hexachlorid, C_2Cl_6 ; propane pentachlorid, $C_3H_2Cl_5$; propane hexachlorid, $C_3H_2Cl_6$; propane heptachlorid, C_3HCl_7 ; propane octachlorid, C_3Cl_8 ; naphthalene tetrachlorid $C_{10}H_4Cl_4$; and hexachlorobenzol, C_6Cl_6 . Other suitable halogenated hydrocarbons are hexabrom butane, $C_4H_4Br_6$; hexabromethane, C_2Br_6 ; and mixed substitution compounds containing more than one of the 20 halogens, such as tetrachlorid brom-ethane, $C_2Cl_4Br_2$. I do not desire to be restricted to the use of these specific substances, or of this class of substances, since any material having the requisite properties, or any mixture of such materials, may be employed within the scope of my invention.

Some of the numerous applications of my invention are illustrated in the accompanying drawing. Fig. 1 shows an ordinary inclosed or cartridge fuse adapted for high-tension service and consisting of a tubular casing 1, which may be of paper, fiber or other suitable non-conducting material, provided with metallic caps or ferrules 2, to 30 which terminals 3 are welded or otherwise attached. A wire or strip 4, of a fusible metal or alloy, is inclosed within the casing 1 and is electrically connected, by soldering or otherwise, to both of the ferrules 2. The 35 space between the wire 4 and the walls of the casing 1 is partly or entirely filled with one of the arc-preventing substances enumerated above, for example, ethane hexachlorid, which is a pulverulent body that 40 may readily be poured into the casing.

In Fig. 2, a modified form of cartridge fuse is shown, in which the fusible metal is formed into a tube 7, inclosing a mass 8 of ethane hexachlorid or other suitable substance. The ends of the tube are pressed together and bent over, forming contact 50 terminal members 9.

Fig. 3 shows an ordinary fuse wire 10 provided with a coating 11 of ethane hexachlorid or the like. This simple form of fuse is perfectly safe, even in the vicinity of inflammable bodies such as draperies and the like, because of the positive and very rapid fire-preventing action of the halogenated substances mentioned above. It may 60 therefore be frequently substituted for cartridge fuses, at a considerable saving in expense.

A modification of the fuse shown in Fig. 65 3 is illustrated in Fig. 4, which shows a

flat strip or ribbon 12 of fusible metal, provided at intervals with perforations 13 which are filled with the fire-preventing material. Since the cross-sectional area of the strip is decreased at these perforations, and 70 the resistance correspondingly increased, the fuse will invariably "blow" at one or more of these points, and the melting of the metal will be accompanied by the volatilization of the fire-preventing substance. The perforations 13 may extend either partly or completely through the strip 12.

Fig. 5 shows a cartridge fuse in which the structures shown in Figs. 1 and 3 are combined. The fuse consists of an insulating tubular casing 14, ferrules 15 and terminals 16 similar to those shown in Fig. 1, together with a fuse wire 17 which, like the wire shown in Fig. 3, is provided with a coating 18 of ethane hexachlorid or the like.

Another modified form of fuse is illustrated in Fig. 6, which shows a tube 19 of fusible metal, into the ends of which terminal contact members 20 are inserted and 90 firmly secured. The ends of the terminal members 20 may be bent into hooks 21, as shown, for convenient attachment to binding posts, and the space 22 between the ends of the terminal members 20, within the tube 95 19, is partly or wholly filled with ethane hexachlorid or other fire-preventing substance of the kind described above. When current passes from one of the terminals 20 to the other, it traverses the relatively thin 100 wall of the tube 19 between the ends of the terminals, and, in case of overload, the fuse will melt at this point and will vaporize the chlorinated hydrocarbon.

A further modification of my invention, 105 as applied to a fuse wire, is shown in Fig. 7. A wire 23, of fusible metal, is reduced in cross-sectional area at one or more places 24, and ethane hexachlorid, or other suitable material, is applied at these reduced portions of the wire, in such quantity that the total diameter at these points is substantially the same as that of the remainder of the wire. Fusion of the wire will, of course, 110 occur first at the reduced portions, and the adjacent fire-preventing material will be vaporized.

Many other structural embodiments of my invention may obviously be devised, and it is therefore to be understood that the structures which I have shown and described are merely illustrative. It is also to be understood that my invention comprehends the use of all solid and semi-solid non-explosive substances that can be volatilized into a fire-preventing vapor, and that no limitations are to be imposed upon my invention except such as are indicated in the appended claims.

I claim as my invention:

1. A safety fuse for electric circuit control 130

comprising a body of readily fusible conducting material in contact with a non-liquid, non-explosive, vaporizable fire-preventing material.

5 2. A safety fuse for electric circuit control comprising a body of readily fusible conducting material associated with a non-fluid, non-explosive, halogenated carbon compound that is volatilizable into a fire-preventing

10 vapor.

3. A safety fuse for electric circuit control comprising a body of readily fusible conducting material associated with a non-fluid chlorinated carbon compound that is vola-

15 tilizable into a fire-preventing vapor.

4. A safety fuse for electric circuit control comprising a body of readily fusible conducting material associated with an ethane polyhalid.

20 5. A safety fuse for electric circuit control comprising a body of readily fusible conducting material associated with ethane hexachlorid.

6. A safety fuse for electric circuit control 25 comprising a body of readily fusible conducting material at least partly surrounded by a non-liquid, wholly vaporizable and non-explosive fire-preventing material.

7. A safety fuse for electric circuit control 30 comprising a casing, a body of fusible conducting material disposed therein, and a body of non-liquid, non-explosive vaporizable fire-preventing material disposed ad-

jacent to and in contact with the said body of fusible material.

8. A safety fuse for electric circuit control comprising a casing, a body of fusible conducting material disposed therein, and a body of non-liquid, non-explosive and wholly vaporizable fire-preventing material 40 at least partly surrounding the said body of conducting material.

9. A safety fuse for electric circuit control comprising a body of fusible conducting material having at least one portion of reduced cross-sectional area, and a body of non-explosive and wholly vaporizable fire-preventing material disposed adjacent to the reduced portion of the said fusible material.

10. A safety fuse for electric circuit control comprising a body of fusible conducting material carrying a body of solid or semi-solid vaporizable and non-explosive fire-preventing material.

11. A safety fuse for electric circuit control comprising a body of fusible conducting material carrying a body of solid or semi-solid halogenated carbon compound that is volatilizable into a fire-preventing vapor.

In testimony whereof, I have hereunto 60 subscribed my name this 19th day of March, 1915.

WALTER O. SNELLING.
